United States Patent Office

Des. 197,844
Patented Mar. 31, 1964

197,844

CHAIR

Diedrich F. Rixmann, St. Louis, Mo., assignor to Contour
Chair-Lounge Co., Inc., St. Louis, Mo., a corporation
of Missouri

Filed Oct. 19, 1962, Ser. No. 72,197

Term of patent 14 years

(Cl. D15—11)

Fig. 1.

Fig. 2.

Fig. 3.

Fig. 4.

Fig. 5.

FIGURE 1 is a side elevational view of a chair showing my new design;

FIGURE 2 is a top plan view thereof;

FIGURE 3 is a front elevational view thereof;

FIGURE 4 is a rear elevational view thereof; and

FIGURE 5 is a front perspective view thereof.

The dominant features of my design reside in the configuration of the chair arms in association with the entire chair, all as shown.

I claim:

The ornamental design for a chair, as shown and described.
